UNITED STATES PATENT OFFICE

94,878

DESIGN FOR WRAPPING PAPER OR SIMILAR ARTICLE

Maurice A. Easter, Nashua, N. H., assignor to
Brown Durrell Co., Boston, Mass., a corpora-
tion of Massachusetts

Application November 7, 1934, Serial No. 53,922

Term of patent 7 years

To all whom it may concern:

Be it known that I, Maurice A. Easter, a citizen of the United States, residing at Nashua, county of Hillsborough, and State of New Hampshire, have invented a new, original, and ornamental Design for Wrapping Paper or Similar Article, adapted particularly as a box cover paper or the like, of which the following is a specification, reference being had to the accompanying drawing, forming part thereof.

The figure is a plan view of a small piece of

paper showing my new design, a complete unit of which is comprised within the transverse dimension *a* and the vertical dimension *b* as indicated thereon, the view being extended to indicate the extension or repeat of the design to cover a desired area.

I claim:

The ornamental design for wrapping paper or similar article as shown and described.

MAURICE A. EASTER.
